PROCESS FOR PURIFYING EXHAUST GASES

Filed Dec. 8, 1942

INVENTOR
BERNARDO BARINGOLTZ

BY Ole Hennk
his ATTORNEY.

UNITED STATES PATENT OFFICE

2,409,825

PROCESS FOR PURIFYING EXHAUST GASES

Bernardo Baringoltz, Pedemar, Argentina

Application December 8, 1942, Serial No. 468,243

1 Claim. (Cl. 23—2)

1

The invention relates to a device which serves as a silencer and disintoxicator of the escape gases of internal combustion engines, which may be added advantageously at the escape tube of the engine, as it will not only enable to silence the noise produced by the combustion, but also to disintoxicate completely the escape gases, causing thus the disappearance of a highly felt, present inconvenience.

At continuation one constructive way of said device will be specified by means of a preferred example of execution of the invention, wherein

Figure 1 is a vertical, longitudinal cut through the device,

Figure 2 a vertical view of the device seen from the left end of Figure 1, and

Figure 3 a similar vertical view of the device seen from the right end of Figure 1.

The novel device to which the invention relates, is preferably cylindrical in shape, although this is not indispensable, and it is composed of a principal chamber 1, wherein is inserted a box 2 of much smaller dimensions, provided with a perforated bottom 3 and reposing within principal chamber 1 upon frame or pedestal 4. Said chamber 2 will contain a filling 5 which consists of a granulated chemical compound which transforms the carbon oxide of the escape gases into carbon dioxide by catalytic oxidation; for example, it can be made up by a mixture which contains

	Per cent
Potassium chlorate	20
Manganese oxide	20
Iron oxide	20
Copper oxide	20
Calcium carbide	20

In the middle of its top, box 2 is provided with a tube 6 which is doubled so as to fit hermetically with another tube of horizontal position 7 which passes through the lateral wall 8 of principal chamber 1, so as to extend to the escape tube 9 of the motor (not shown), wherewith it forms, for example by means of flanges 10, an hermetic connection.

Principal chamber 1, at the side opposed to lateral wall 8, is closed by a division 11. Also said principal chamber 1 contains more or less up to two thirds of its height and surrounding box 2 and tubes 6 and 7, a granulated filling of another chemical compound 32, the purpose of which is to absorb the carbon dioxide which is formed in box 2, as well as the other combustion gases. Said compound may consist for example of a mixture of

	Per cent
Calcium oxide	50
Iron sulphate	20
Caustic soda	30

2

Division 11 may be fixed to cylindrical wall 12 of principal chamber 1, for example, by means of a ring 13 combined with a groove 14, wherein equally will be retained a bell 15, in communication with principal chamber 1 by means of an opening 16 arranged at the upper part of division 11 and protected by a metal web 17, preferably somewhat bulging towards principal chamber 1. From said opening 16 there parts, descending obliquely, a tube 18 which ends at the center of bell 15 which is left open at its narrow hind-end 19, so that bell 15 forms a chamber 20 wherein a first retention of solid organic particles or corpuscles is produced.

The general body of the device formed in its first part by principal chamber 1 continues to extend to the other side, containing within its cylindrical walls 12 behind the first bell 15 a second bell 21 wherein first bell 15 encases, occupying the central part thereof with its open end 19. This second bell 21, contrary to first bell 15, is closed in the shape of a truncated cone by wall 22. This second bell 21 is seated upon a horizontal division 23 which extends to the second body 24, and said second bell 21 furthermore is retained by clamps 25 fixed at 26 to the vertical wall of said second body 24.

The second body 24, which just has been mentioned, is fixed hermetically to the general body of the device, for example, by means of a ring 27 which within a groove 27' embraces the doubled ends of both walls of the two bodies, viz. of the general body and of second body 24. Said connecting ring 27 will be divided into halves, being thus unmountable, and it can be adjusted hermetically by means of screwpins so as to form an absolutely hermetic union between both bodies.

This second body 24 contains a retention box 29 for solid particles 28, and so as to retain said box 29 within the interior of body 24, said body, for example, may be provided with soldered legs 28. Said box 29 will have as a wall metal webs 30, and to said walls 30 preferably an oblique inclination will be given, such as shown in Figure 1. Finally, second body 24 terminates in the outlet tube 31 wherethrough issue to the atmosphere only completely disintoxicated gases, the run of which through the device from escape tube 9 to said outlet tube 31 it is worth while to describe briefly.

Said gases pass from escape tube 9 of the engine through tube 7 continued by tube 6 to box 2 wherein they cross the layer of the granulated chemical compound 5, so as to pass through the perforated bottom 3 of said box 2 and get scattered, raising from pedestal 4 through the second layer of the other granulated chemical compound 32, so as to pass through opening 16 of division 11 to tube 18, wherfrom, issuing at 19, they will

hit against back wall 22 of second bell 21. These runs and hits will provoke the precipitation of the solid particles which accumulate at bottom 20 of first bell 15, as well as beneath second bell 21, whereas the light parts, viz., the gases, will raise along the upper wall of second bell 21 so as to pass to second body 24, wherein again they will meet with metal web walls 30 which serve for retaining the last solid particles which may have reached until there. To said walls 30 the oblique inclination shown in Figure 1 has been given so as to lessen the hit of the gases against said walls 30, and, finally, after having passed also through said two walls 30, the purified gases, made innocuous, will escape through outlet tube 31.

I claim:

A process for purifying the exhaust gases from internal combustion engines, which comprises first treating said gases with an agent consisting of the following components in approximately the stated proportions: 20% potassium chlorate, 20% manganese oxide, 20% iron oxide, 20% copper oxide, and 20% calcium carbide, so as to transform the carbon monoxide present in the exhaust gases into carbon dioxide, and immediately thereafter treating said gases with an absorbing agent consisting of the following components in approximately the stated proportions: 50% calcium oxide, 20% iron sulphate, and 30% caustic soda.

BERNARDO BARINGOLTZ.
